United States Patent Office.

WEBSTER GILLETT, OF YPSILANTI, MICHIGAN.

Letters Patent No. 94,198, dated August 31, 1869.

IMPROVEMENT IN ELECTRO-MAGNETIC ALARMS FOR RAILROAD-CARS.

The Schedule referred to in these Letters Patent and making part of the same.

To all whom it may concern:

Be it known that I, WEBSTER GILLETT, of Ypsilanti, in the county of Washtenaw, and State of Michigan, have invented certain new and useful Improvements in Accident Alarm-Telegraph for Railroad-Cars; and I do hereby declare that the following is a full and complete description of the same, reference being had to the accompanying drawings, making part of this specification, in which—

Figure 1 is an end view of the apparatus and section of a car-truck.

Figure 2, a view of the under side.

Figure 3, a side view of the apparatus detached.

Figures 4 and 5, detached sections.

Like letters of reference refer to like parts in the different views.

This invention has for its object the signalling to the engineer of a train, the event of an accident to any one of the cars, such as the breaking down of the running-gear, or in the event of being thrown from the track, or becoming detached, the alarm being given by telegraphic communication and apparatus, the same being operated by certain devices in connection therewith and attached to each car, and detached only in the event of accidents of the nature aforesaid.

In fig. 1, A B represent a pair of truck-wheels of a railroad-car, and C, the frame, in which said wheels are secured, and upon which the car, represented by D, is supported, by the intervention of the cross-beam D, fig. 3.

The extreme ends of said beam are secured between the standards *a* of the frame, and rest upon rubber springs E.

Immediately below the beam referred to is a secondary beam, F, the ends of which are also secured between the cheeks of the standards *a* referred to.

To the under side of the beam F is pivoted one end of the transverse lever G, fig. 3, through the intervention of the stays H, whereas the opposite ends are secured in the slot of the stay I, fig. 1, in which they are free to move upward and downward, as and for a purpose hereinafter shown.

J is a stem, one end of which is pivoted to the end of the lever G, and retained in a vertical position, by means of the stay K, in which it is loosely fitted, thereby allowing it to play upward and downward, on the movement of the levers.

Surrounding the upper part of the stem is a coiled spring, *a'*, the purpose of which is to return the levers to the position shown, after being pushed upward, as will presently be described.

To said stem is attached one section of the circuit-breakers L, a detached view of which is shown in figs. 4 and 5. Said attachment is made by means of the lug *b*.

One section of each circuit-breaker is connected to another by the insulated wire *e*, whereby they are actuated conjointly, by means of the levers G, to which they are connected by means of the stems J referred to, whereas each of the other sections of the circuit-breakers is connected, the one to an electric battery, indicated by the dotted lines *d*, fig. 1, by means of the insulated wire N, and the other to an electro-apparatus, O, by means of the wire P.

Said apparatus and battery are the same as those in ordinary use, and are placed upon the locomotive within reach and hearing of the engineer, whose immediate attention it is especially designed to call.

It will be observed that the immediate connections of the devices, consisting of the transverse levers G, circuit-breakers, &c., to the battery and apparatus, are effected by the coiled connections R R', whereby is prevented any undue strain being exerted upon them in consequence of the vertical and longitudinal movement of the cars, and therefore less liable to break, than were said connections of a more rigid character.

A similar arrangement of devices as that above described is secured to the bottom of each car, substantially in the same way and place.

The immediate connection of the conducting insulated wire from car to car, thence to the battery and apparatus, may be effected by any easy and appropriate device, the connection being made at the same time of coupling up the train.

Having thus described the construction and arrangement of the signalling-apparatus, the practical operation of the same is as follows:

It will be observed that the actuating-levers G are arranged near the bed of the track, being but a few inches above the top of the ties.

Now, should any obstruction be presented sufficiently to come in contact with the levers, they would be thrown upward, actuating the circuit-breakers, thereby breaking the circuit, which sounds an alarm on the bell Q, thus giving timely notice, to the engineer, of danger.

Or, should one of the cars be thrown from the track, or in such way break down, that the levers would come to the ground, the fact is instantly made known to the engineer, by breaking of the circuit actuated by the levers, and, by such timely warning, the train is stopped before further accident can occur.

By this device, it will be obvious that many dangers to life, occasioned by the breaking down of an axle, or some other part of the truck, or of a car being thrown from the track, are avoided, as the immediate and timely notice, given to the engineer, enables him to stop his train in time to prevent a continuation and aggravation of the accident, and thus greater safety is secured to the passengers and train.

The construction and arrangement of the apparatus

are simple, and of easy manipulation, and, at all times certain in their operation, as the mere breaking of the connection, at any part of the general circuit, sounds an alarm in time for the engineer to stop his train.

What I claim as my improvement, and desire to secure by Letters Patent, is—

1. The transverse actuating-levers G, stem J, and spring α , as arranged in combination with the circuit-breakers L, in the manner substantially as and for the purpose set forth.

2. The transverse actuating-levers G, circuit-breakers L, as arranged in relation to and in combination with the battery C and signalling-apparatus O, in the manner substantially as described, and for the purpose specified.

WEBSTER GILLETT.
